Primary Examiner—Cathron C. Brooks

(74) Attorney, Agent, or Firm—Amster, Rothstein & Ebenstein LLP

(57) CLAIM

The ornamental design for a storage box, as shown and described.

DESCRIPTION

The sole FIGURE is a front perspective view of a storage box showing my new design.

The broken lines are for illustrative purposes only and form no part of the claimed design.

1 Claim, 1 Drawing Sheet
